UNITED STATES PATENT OFFICE.

LOUIS STEINBERGER, OF NEW YORK, N. Y.

INSULATOR FOR LEADING-IN CABLES, &c.

No. 844,208.

Specification of Letters Patent.

Patented Feb. 12, 1907.

Application filed February 21, 1906. Serial No. 302,209.

To all whom it may concern:

Be it known that I, LOUIS STEINBERGER, a citizen of the United States, and a resident of the city of New York, borough of Brooklyn, in the county of Kings and State of New York, have invented a new and Improved Insulator for Leading-In Cables, &c., of which the following is a full, clear, and exact description.

10 My invention relates to insulators, and more particularly to a type of insulator for leading-in cables and other conductors and admitting of use generally wherever it is desirable for a conductor carrying a high-potential or heavy current to pass through a wall, roof, or partition of any kind.

15 Among the several objects of my invention are the following: first, to facilitate drainage in order to keep all of the internal parts of 20 the insulator and their connections as dry as possible; second, to give the insulator a maximum of mechanical strength; third, to render the supporting-plates of the insulator reversible in order that after long use their 25 period of utility may be prolonged; fourth, to provide the inner and outer supporting-plates with shields and drain-surfaces of a kind adapted to remove moisture with the greatest facility and at the same time to prevent 30 vent rain, snow, or sleet from moistening the entire surface of the plates; fifth, to render the several supporting-plates as far as practicable independent of each other; sixth, to prevent the creeping of moisture from one 35 part of the insulator to another; seventh, to increase the insulating-surface within a given space and to produce an insulator of this type that may be readily mounted into operative position or removed therefrom.

40 Reference is to be had to the accompanying drawings, forming a part of this specification, in which similar characters of reference indicate corresponding parts in all the figures.

45 Figure 1 is a front elevation showing my device as applied to a wall and as ready to receive the leading-in cable or other conductor. Fig. 2 is a vertical section through the same upon the line 2 2 of Fig. 1, showing the shape 50 of the central inner and outer supporting-plates and of the clamping members of insulating material joining the inner and outer supporting-plates together. Fig. 3 is a front elevation of the device with the front supporting-plate removed; and Fig. 4 is a fragmentary vertical section through the outer

supporting-plate, showing it as reversed so as to present a different surface to the weather.

A wall is shown at 5 and is provided with a circular aperture 6. Mounted within this 60 aperture is a central member 7, of insulating material, having the form of a disk and held in position by lugs 8, disposed upon opposite sides. This member I designate as the "central supporting-plate." The lugs 8 are held 65 in position by fastenings 9. The central supporting-plate 7 is provided with a central aperture 10 of cylindrical form, this aperture being smooth, as indicated in Fig. 2. A frusto-pyramidal member 11, of insulating 70 material, is fitted against the central supporting-plate 7 and is provided with annular steps 12, spaced apart, as shown in Fig. 2. This frusto-conical member is provided with a stem 13, projecting laterally therefrom and 75 threaded externally. Through the frusto-conical member 11 and the stem 13 there passes a cylindrical bore 14. The end 15 of the stem 13 is smooth. The apex 13^a of the frusto-conical member 11 has the annular 80 form, as indicated in Figs. 1 and 2. A revoluble nut 16, of insulating material, is threaded internally and is provided with annular steps 17, spaced apart, as indicated in Fig. 2. This revoluble nut may be of substantially 85 the same size as the frusto-conical member 11. Two supporting-plates 18 are made substantially alike and engage stationary lugs 8^a, held in position by fastenings 9^a. Each supporting-plate 18 is provided 90 with a smooth annular surface 19, which is engaged by a series of revoluble buttons 20. By turning these buttons the plate may be taken out or replaced. An annular portion 21 of each supporting-plate is rendered 95 smooth, as will be understood from Fig. 1. Integral with each supporting-plate 18 are longitudinal hoods 22, provided with undercuts 23. The hoods 22 are so arranged as to resemble a succession of inverted V's, as will 100 be understood from Fig. 1. The undercuts 23 are for the purpose of preventing surface leakage and also for partially enlarging the surfaces of the supporting-plates. Each supporting-plate 18 is further provided with 105 horizontal hoods 24, provided with undercuts 25. Upon its opposite face each supporting-plate 18 is provided with longitudinal hoods 26, bounded by flat surfaces or steps 27. The general disposition of the 110 hoods 26 is the same as that of the hoods 22, and below the hoods 26 are longitudinal hoods

23, arranged horizontally and corresponding to the general location of the hoods 24.

The supporting-plates 18 are made exactly alike and are distinguished from each other merely by their relative positions. One of them—for instance, the one at the left of Fig. 2—is employed outside of the building, being exposed directly to the weather. The other—say, the one at the right of Fig. 2—is used inside of the building. If any moisture falls upon the outer supporting-plate, this moisture is drained obliquely downward and away from the center of the plate, so that the conductor passing through the bore 14 is drained comparatively dry. It will be understood that a surface inclined obliquely downward tends to guide drops of rain-water, even if the latter depend from the lower edge and are supported for adhering to the same. If a drop falls from one of the hoods 22, it will have but little tendency to lodge upon the next lower hood; but should it be so the latter will guide it obliquely downward, the upper hoods overhanging the lower ones, as will be understood from Fig. 2. If under usage it may happen that one or both of the supporting-plates 18 become roughened or coated with smoke or other impurities which causes it to offer less surface resistance, it is upon this account that the supporting-plates 18 are rendered reversible, and to reverse one of these plates all that is necessary is to turn the buttons 20, take out the plate, turn it around, replace it, and restore the buttons 20 to their original positions.

It will be seen from Fig. 2 that the supporting-plates 18 and the supporting-plate 7 are to a great extent independent of each other—that is to say, one or both of the plates 18 may be removed without affecting the supporting-plate 7. The latter may continue to support the frusto-conical member 11 and the nut 16, together with any cable or other conductor which may pass through the bore 14. In order to remove the frusto-conical member 11, the nut 16 is simply screwed off the stem 13, and the frusto-conical member 11 is then removed to the left, according to the view shown in Fig. 2.

In wireless telegraphy the bore 14 may be used to support the lower part of the antenna, this lower part being commonly designated in the art as the "cow's-tail." While there is no essential difference between the supporting-plates 18, for convenience I designate the one exposed outwardly to the weather as the "front supporting-plate," and the other as the "rear supporting-plate." The member 7 I designate, by way of contradistinction, as the "middle" supporting-plate.

I do not limit myself to the exact form nor to the details of construction and arrangement of any or all of the parts shown and described, as it will be apparent to those skilled

in the art that changes may be made therein without departing from the spirit or scope of my invention. Nor do I limit myself to the use of any prescribed materials. I prefer, however, to employ the insulating material known in the art as "electrose."

Having thus described my invention, I claim as new and desire to secure by Letters Patent—

1. The combination of a supporting-plate 75 provided with an aperture, a frusto-conical member engaging said supporting-plate and provided with a tubular stem projecting through said aperture, and means for locking said frusto-conical member against said supporting-plate.

2. An insulator, comprising a supporting-plate provided with an aperture, a member of insulating material provided with a surface for engaging said supporting-plate and further provided with a tubular member for extending through said aperture, and a member connected with said tubular member and engaging said supporting-plate for the purpose of locking said member of insulating 90 material in position.

3. An insulator, comprising a supporting-plate of insulating material, a frusto-conical member engaging the same and provided with annular steps for preventing surface 95 leakage, said frusto-conical member being further provided with a tubular stem, and a nut of insulating material mounted upon said stem and engaging said supporting-plate.

4. An insulator, comprising a supporting-plate of insulating material provided with an aperture, a substantially frusto-conical member of insulating material engaging said supporting-plate and provided with a tubular stem passing through said aperture, and a 105 nut of insulating material engaging said stem and also engaging said supporting-plate.

5. An insulator, comprising a supporting-plate provided with a central aperture, a member of insulating material provided with a central bore and with a tubular portion extending through said aperture, said tubular portion being threaded, and a nut of insulating material also threaded, said nut engaging said supporting-plate and also engaging said tubular portion.

6. An insulator, comprising a supporting-plate of insulating material provided with an aperture, a member of insulating material provided with a portion extending through 120 said aperture and threaded, and a threaded nut engaging said portion last-mentioned and also engaging said supporting-plate, said threaded nut having substantially a frusto-conical form.

7. An insulator, comprising a central supporting-plate provided with an aperture, inner and outer supporting-plates mounted upon opposite sides of said first-mentioned supporting-plate, a member of insulating 130

- material provided with a cylindrical bore and engaging all of said supporting-plates, and means for locking said member of insulating material rigidly in relation to said first-mentioned supporting-plate.
8. An insulator, comprising a supporting-plate provided with an aperture, an insulating member having a substantially frusto-conical portion provided with annular steps concentric to each other, said member being further provided with a tubular stem projecting through said aperture, and a nut of insulating material engaging said tubular stem and also engaging said supporting-plate.
9. An insulator, comprising a plate of insulating material provided with an aperture, a member of insulating material provided with a cylindrical bore for engaging a conductor, and a nut of insulating material engaging said supporting-plate and also engaging said member of insulating material, said nut of insulating material being provided with a plurality of concentric annular steps for preventing surface leakage.
10. An article of manufacture, a supporting-plate provided with longitudinal hoods provided with drip edges inclined relatively to the horizon for the purpose of drifting moisture, said supporting-plate being further provided with a central aperture.
11. As an article of manufacture, a supporting-plate provided upon one of its faces with a plurality of longitudinal hoods integral therewith, said hoods each being provided with an undercut, said plate being further provided with a central aperture.
12. As an article of manufacture, a supporting-plate provided with a plurality of projecting hoods, one overhanging another, and one projecting farther than another from the body portion of said supporting-plate so as to overhang the same, said supporting-plate being provided with an aperture.
13. As an article of manufacture, a supporting-plate provided adjacent to its outer edge with an annular smooth portion, and provided with a central aperture, said supporting-plate being further provided with hoods disposed intermediate of its outer edge and said aperture.
14. The combination of a supporting plate or partition provided with an aperture, an insulating member engaging said supporting-plate and provided with a tubular stem projecting through said aperture, and a detachable insulating locking member engaging said tubular stem.
15. An insulator, comprising a member of insulating material provided with a tubular stem, and a detachable insulating locking member connected to said tubular stem.
16. An insulator, comprising a body mem-
- ber of insulating material provided with a reduced portion and with an aperture extending through said body member and said reduced portion, and a locking member of insulating material provided with an aperture for engaging the said reduced portion of said body member.
17. An insulator, comprising a member of insulating material provided with a threaded stem, and a nut engaging said threaded stem for the purpose of locking said member to a partition or wall.
18. An insulator, comprising a body portion of insulating material provided with a threaded stem, and a detachable member of insulating material connected to said threaded stem for the purpose of locking said body portion to a partition or wall.
19. An insulator, comprising a body member provided with a substantially conical head portion having annular surfaces of different diameters, and also provided with a stem, an aperture extending through said body member and said stem, a detachable insulating member provided with a substantially conical head portion having annular surfaces of different diameters connected to said stem, and means for locking said detachable member on said stem.
20. In an insulator, the combination of a supporting plate or partition provided with an aperture, an insulating member provided with a substantially conical portion connected to said supporting plate or partition and provided with a threaded tubular stem projecting through said aperture.
21. In an insulator, the combination of a supporting plate or partition provided with an aperture, an insulating member provided with a substantially conical head portion connected to said supporting plate or partition, and further provided with a threaded tubular stem extending through said aperture, and a detachable insulating threaded locking member engaging said threaded tubular stem.
22. An insulator, comprising a body member provided with a substantially conical head portion having annular surfaces of different diameters, and also provided with a stem, an aperture extending through said body member and said stem, a detachable insulating member connected to said stem, and means for locking said detachable insulating member on said stem.
